UNITED STATES PATENT OFFICE

ALBERT E. WOOLNOUGH, OF ST. ALBANS, NEW YORK

DESIGN FOR A TOY ANIMAL

Application filed September 9, 1929. Serial No. 32,699. Term of patent 14 years.

To all whom it may concern:

Be it known that I, ALBERT E. WOOLNOUGH, a citizen of the United States, residing at St. Albans, Long Island, in the county of Queens and State of New York, have invented a new, original, and ornamental Design for Toy Animals, of which the following is a specification, reference being had to the accompanying drawing, forming part thereof.

Figs. 1, 2, and 3 are side, front, and rear views respectively, of a toy animal, showing my new design.

I claim:

The ornamental design for a toy animal, as shown.

ALBERT E. WOOLNOUGH.
